COVERING MEMBER FOR ARTICLES
OF LUGGAGE

Louis H. Clark, New York, N. Y.

Application August 2, 1946, Serial No. 687,893

5 Claims. (Cl. 229—32)

1

This invention relates to new and useful improvements in the construction of an article of luggage.

An object of the invention is to provide an article of luggage comprised of two sections of similar construction, each being formed with a one-piece outer covering member and an inner tray member, the two sections differing only in the disposition of certain tab elements in the covering member.

Another object is to provide an article of luggage comprised of two sections, each of which has an inner tray member with a frame and a one-piece receptacle element.

Still another object is to provide blanks from which the covering members and the receptacle elements of the tray members can be readily made in large quantities and at low unit cost.

A further object is to provide an article of luggage which is attractive in appearance and is constructed to endure hard usage.

These and other objects are accomplished in brief, by providing an article of luggage comprised of two similarly constructed sections, each of which has an outer covering and an inner tray member disposed therein. The covering is in one piece and has a bottom wall, a front and a rear wall integral with the bottom wall, reinforced side walls set in slightly and consisting of an outer wall integral with the bottom wall and an inner wall which has two wall portions integral with the front and rear walls respectively. In the lower section, the front, rear and side walls have resilient top portions which are folded inwardly and then upwardly to form a shouldered recess over which the upper section can rest. In the upper section, the resilient top portions of the walls are folded over the frame edges and are adapted to be seated in the recess of the lower section. Novel scorings in the outer coverings and a fold in the outer covering blank constitute other features of the invention.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a perspective view of an article of luggage constructed in accordance with the invention herein.

Fig. 2 is a perspective view of the lower of two similarly constructed sections which form the article of luggage shown in Fig. 1.

2

Fig. 3 is a sectional view through the line 3—3 of Fig. 2.

Fig. 4 is a sectional view through the line 4—4 of Fig. 3.

Fig. 5 is a perspective view of the covering member of each section of the article of luggage, prior to its assembly with an inner tray member.

Fig. 6 is a plan view of a blank from which a covering member such as the one shown in Fig. 5 can be made.

Fig. 7 is a sectional view through the line 7—7 of Fig. 6.

Fig. 8 is a perspective view of the inner tray member of each section of the article of luggage.

Fig. 9 is a plan view of a blank from which a receptacle element of an inner tray member, such as the element shown in Fig. 8, can be made.

Fig. 10 is a sectional view in a plane similar to that of Fig. 4 but through the upper section of the article of luggage.

Fig. 11 is a sectional view through the line 11—11 of Fig. 1.

In the drawings and in the specification, in which like reference numbers designate similar parts, an article of luggage 15 is comprised of two similarly constructed sections, a lower section 16 and an upper section 16^a, which differ only in the disposition of certain tab elements in the covering member as will appear fully hereafter. The sections 16 and 16^a can be hingeably joined to each other and provided with the usual carrying handle 17, lock 18 and other coacting fastening elements 19.

Each of the sections 16 and 16^a is formed with an outer member or covering 20 and an inner tray member 21. The outer or covering member 20 can be readily made from a blank such as the covering blank 22, shown in Fig. 6. The blank 22 is a single piece of flat material, such as craft-board, cardboard, fibre, etc., and has two parallel vertical folds 23 held in place by stitches 24. The folds include between them a central quadrilateral portion 25 having top and bottom flaps 26, the junction between the central portion and each flap 26 being defined by a plurality of substantially parallel scorings 27 which extend at right angles to the folds 23. Each flap 26 has a tab 28 whose junction with said flap is marked by a plurality of scorings 29 which are substantially parallel with each other and with the scorings 27. Each flap 26 is further provided with two oppositely disposed quadrilateral wings 30 which extend laterally from the flap and join it along end portions of the stitched fold 23.

Oppositely disposed side flaps 31 extend laterally from the central portion 25, central por-

tions of the stitched fold 23 defining the junction of each side flap 31 with the central portion. Each side flap 31 has two rounded or arcuate edges 31a adjacent the fold 23, and a side flap tab 32 whose junction with the side flap 31 is defined by a plurality of scorings 33 which are approximately parallel with each other and with the stitched folds 23.

The outer or covering member 20 of each section 16 and 16a can be made from the blank 22 as follows:

The blank is folded along the parallel scorings 27 so that the top and bottom flaps extend upwardly, the central portion 25 of the blank forming a bottom wall 34 of the covering member 20, the top and bottom flaps of the blank forming the front and rear walls 35 of the covering member and the series of parallel scorings 27 forming rounded edges 36 between the bottom wall 34 and the front and rear walls 35 and preventing the material from cracking along the lines of fold. The wings 30 are folded inwardly until they are normal to the front and rear walls and their edges 37 are adjacent and parallel, and the side flaps 31 folded upwardly to the outside of the wings 30, forming two ply reinforced side walls 38 of the covering members with the arcuate side flap edges 31a conforming to the rounded edges 36. Staples 39 secure the wings to the side flaps. The folds 23 of the blank form flanges 40 which extend outwardly along the bottom and side edges of each reinforced side wall 38.

If it is desired, a binding 41 can be disposed about and secured to each flange 40 to protect and trim it. With the blank thus folded, top and bottom flap tabs 28 of the blank 22 extend upwardly forming front and rear wall top portions 42 which are resilient due to the scorings 29. Similarly side flap tabs 32 of the blank 22 extend upwardly forming resilient top portions 43 of the reinforced side walls 38 due to the scorings 33 (see Fig. 5). The disposition of the top portions 42 and 43 in the luggage sections 16 and 16a will be described hereafter, following the disclosure relative to the inner tray members 21.

The inner tray member 21 (see Fig. 8) is comprised of a receptacle element 44 and a four sided frame 45. The receptacle element can be readily made from a blank, such as the blank 44a, shown in Fig. 9. The blank 44a is a single piece of flat material cut to provide a quadrilateral body portion 46 with top and bottom tabs 47 whose lines of junction with the body portion 46 are defined by two substantially parallel scorings 48. Two oppositely disposed side flaps 49 extend laterally from central side edge portions 50 of the body portion 46, each side flap 49 being provided with a side flap tab 51 whose line of junction with the side flap is defined by a scoring 52 which is substantially parallel to the body portion side edge portion 50. Each side flap 49 has outwardly bulging or arcuate upper and lower edges 53.

The frame 45 is quadrilateral in shape and comprises two opposite parallel slats 54 and two opposite parallel slats 55 positioned and secured at right angles to the slats 54.

The inner tray member 21 can be made from the blank 44a and the frame 45 as follows:

The blank top and bottom tabs 47 are secured to inner opposing faces of the frame slats 54, and the side flap tabs 51 are secured to inner opposing faces of the frame slats 55. The side flaps 49 then extend downwardly to form side walls 56 of the tray member, and top and bot-

tom portions of the blank body portion 46 extend downwardly to form front and rear tray walls 57, while a central portion of the blank body portion forms the bottom wall 58 of the inner tray member. The side flap arcuate edges 53 are joined to adjacent upper and lower side edge portions 59 of the blank, so that the tray has rounded bottom edges 60 between the bottom and front and rear walls of the tray. The blank scorings 48 and 52 permit the walls 57 and 56 respectively to belly outwardly under the frame.

The lower section 16 (see Figs. 2, 3, 4 and 10) can now be assembled by taking an outer or covering member 20 in the condition described hereinabove, shown in Fig. 5, and disposing therein an inner tray member 21 in the following relationship:

The tray frame slats 54 are positioned with their outer faces extending along the front and rear walls 35 of the outer covering immediately below its resilient top portions 42, and the tray frame slats 55 extending along the reinforced side walls 38 immediately below its resilient top portions 43. Staples 61 extending through the front and rear walls 35 of the outer covering, the frame slats 54 and the inner tray front and rear walls 57, and other staples 61 extending through the side walls 38 of the outer covering, the frame slat 55 and the inner tray side walls 56 retain the members securely in position.

Each top wall portion 42 is folded inwardly and then upwardly along its scorings 29 to form a shoulder 62 and an upwardly extending flange 63. Similarly each top wall portion 43 is folded inwardly and then upwardly along its scorings 33 to form a shoulder 64 and an upwardly extending flange 65. The inner tray bottom wall 58 rests on the outer covering bottom wall 34 with the rounded edges 60 of the tray conforming closely with the rounded edges 36 of the outer covering. The inner tray front and rear walls 57 and side walls 56 extend upwardly and inwardly from the outer covering front and rear walls 35 and side walls 38 to the frame which is disposed between the members below the shoulders 62 and 64.

The assembly of the upper section 16a is similar to the assembly of the lower section 16 except for the disposition of the resilient top wall portions 42 and 43 of the outer covering 20. In section 16a, an outer covering member 20, in the condition described and shown in Fig. 5, has an inner tray member 21 disposed therein as hereinabove described for section 16 and then the top wall portions 42 and 43 of the outer covering are folded along their respective scorings 29 and 33 to cover the top edges of the frame 45 and the upper portions of the tray walls 57 and 56 respectively. More specifically, each top wall portion 42 is folded over with a portion 66 which extends over the top edge of one of the frame slats 54 and a portion 67 which covers an upper portion of the tray wall 57 (see Fig. 10). Similarly, each top wall portion 43 is folded over with a portion 68 which extends over the top edge of one of the frame slats 55 and a portion 69 which covers an upper portion of the tray side wall 56 (see Fig. 11).

Thus constructed, the sections 16 and 16a can be positioned, as shown in Figs. 1 and 11, to form the article of luggage 15. In closed position, the wall edge portions 66 and 68 of section 16a rest on the shoulders 62 and 64 respectively of section 16, with the upwardly extending flanges 63 and

65 of section 16 extending about portions 61 and 69 of the tray of section 16a.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A one-piece blank for forming a covering member of a section of an article of luggage, said blank having a quadrilateral central body portion whose adjacent edges are normal to each other, said central portion being adapted to form the covering bottom wall and having a top and a bottom flap and a plurality of scorings defining the junction of the central portion with each such flap, the top and bottom flaps being adapted to be folded upwardly along said scorings to form the covering front and rear walls with rounded bottom edges, two folds each extending along a side edge of the central portion and the top and bottom flaps at right angles to the above mentioned scorings, two oppositely disposed side flaps extending laterally from the folded side edges of the central portion and adapted to be folded upwardly to form the covering side walls with the folds forming outwardly extending flanges, portions of the side flap edges adjacent the folds being arcuate and conforming to the rounded bottom edges of the covering, two oppositely disposed wings extending laterally from the folded side edges of the top and bottom flaps and adapted to be folded inwardly with respect to and to reinforce the covering side walls, and a tab extending along the outer edge of each of the four flaps and adapted to form resilient top portions of the front, back and side walls of the covering, each tab having three spaced scorings adjacent and parallel to its junction with a flap, that portion of each tab between the outer edge of said tab and the intermediate line of said three score lines having a length which is less than the length of its adjacent flap.

2. In an article of luggage, a section comprising an outer covering member and an inner tray member, the outer covering member having a quadrilateral bottom wall, front and rear walls integral with and extending upwardly from the front and rear edges of the bottom wall, two opposing reinforced side walls each comprising an outer side wall integral with and extending upwardly from a side edge of the bottom wall and an inner side wall formed with two similar wall portions, one of said inner wall portions extending inwardly from and being integral with the front wall and the other said inner wall portion extending inwardly from and being integral with the rear wall, and the front, rear and outer side walls each having a resilient top portion, and the inner tray member comprising a receptacle element and a four sided frame, the receptacle element having a quadrilateral body portion, a top and a bottom tab integral with said body portion and extending along its top and bottom edges, two side flaps integral with said body portion and extending along its other two opposite edges intermediate their ends, a side flap tab integral with each receptacle side flap and extending along its outer side edge, said receptacle being disposed with its top and bottom tabs extending along opposite frame sides, the receptacle body portion ex-

tending downwardly forming front, rear and bottom walls of the tray member, the two side flap tabs extending along the other two frame sides and the receptacle side flaps extending downwardly forming side walls of the tray member, the inner tray member being disposed within the covering member with the tray frame uppermost and the resilient top portions of the covering walls extending inwardly above the frame and then upwardly to form a recess extending about the top of the covering member.

3. In an article of luggage, a section comprising an outer covering member and an inner tray member, the outer covering member having a quadrilateral bottom wall, front and rear walls integral with and extending upwardly from the front and rear edges of the bottom wall, the bottoms of the front and rear walls curving inwardly and downwardly to join the bottom wall, two opposing reinforced side walls with rounded bottom corners, each reinforced side wall comprising an outer side wall integral with and extending upwardly from a side edge of the bottom wall and an inner side wall formed with two similar wall portions, one of said inner wall portions extending inwardly from and being integral with the front wall and the other said inner wall portion extending inwardly from and being integral with the rear wall, and the front, rear and outer side walls each having a resilient top portion, and the inner tray member comprising a receptacle element and a four sided frame, the receptacle element having a quadrilateral body portion, a top and a bottom tab integral with said body portion and extending along its top and bottom edges, two side flaps integral with said body portion and extending along its other two opposite edges intermediate their ends, a side flap tab integral with each receptacle side flap and extending along its outer side edge, said receptacle being disposed with its top and bottom tabs extending along opposite frame sides, the receptacle body portion extending downwardly forming front, rear and bottom walls of the tray member, the two side flap tabs extending along the other two frame sides and the receptacle side flaps extending downwardly forming side walls of the tray member, the inner tray member being disposed within the covering member with the tray frame uppermost and the resilient top portions of the covering walls extending inwardly above the frame and then upwardly to form a recess extending about the top of the covering member.

4. In an article of luggage, a section comprising an outer covering member and an inner tray member, the outer member having a quadrilateral bottom wall, front and rear walls integral with and extending upwardly from the front and rear edges of the bottom wall, the bottoms of the front and rear walls being rounded, two opposing reinforced side walls set slightly in from the bottom side edge and having rounded bottom corners, each reinforced side wall comprising an outer side wall integral with and extending upwardly from a side edge of the bottom wall and an inner side wall formed with two similar wall portions, one of said inner wall portions extending inwardly from and being integral with the front wall and the other said inner wall portion extending inwardly from and being integral with the rear wall, and the front, rear and outer side walls each having a resilient top portion, and the inner tray member comprising a receptacle element and a four sided frame, the receptacle element having a quadrilateral body portion, a top and a bottom tab integral with said body portion and extending along its top and bottom edges, two side flaps integral with said body portion and extending along its other two opposite edges intermediate their ends, a side flap tab integral with each receptacle side flap and extending along its outer side edge, said receptacle being disposed with its top and bottom tabs extending along opposite frame sides, the receptacle body portion ex-

ment having a quadrilateral body portion, a top and a bottom tab integral with said body portion and extending along its top and bottom edges, two side flaps integral with said body portion and extending along its other two opposite edges intermediate their ends, a side flap tab integral with each receptacle side flap and extending along its outer side edge, said receptacle being disposed with its top and bottom tabs extending along opposite frame sides, the receptacle body portion extending downwardly forming front, rear and bottom walls of the tray member, the two side flap tabs extending along the other two frame sides and the receptacle side flaps extending downwardly forming side walls of the tray member, the inner tray member being disposed within the covering member with the tray frame uppermost and the resilient top portions of the covering walls extending inwardly above the frame and then upwardly to form a recess extending about the top of the covering member.

5. In an article of luggage, a section comprising an outer covering member and an inner tray member, the outer covering member having a quadrilateral bottom wall, front and rear walls integral with and extending upwardly from the front and rear edges of the bottom wall, two opposing reinforced side walls each comprising an outer side wall integral with and extending upwardly from a side edge of the bottom wall and an inner side wall formed with two similar wall portions, one of said inner wall portions extending inwardly from and being integral with the front wall and the other said inner wall portion extending inwardly from and being integral with the rear wall, and the front, rear and outer side walls each having a resilient top portion, and the inner tray member comprising a receptacle ele-

ment and a four sided frame; the receptacle element having a quadrilateral body portion, a top and a bottom tab integral with said body portion and extending along its top and bottom edges, two side flaps integral with said body portion and extending along its other two opposite edges intermediate their ends, a side flap tab integral with each receptacle side flap and extending along its outer side edge, said receptacle being disposed with its top and bottom tabs extending along opposite frame sides, the receptacle body portion extending downwardly forming front, rear and bottom walls of the tray member, the two side flap tabs extending along the other two frame sides and the receptacle side flaps extending downwardly forming side walls of the tray member, the inner tray member being disposed within the covering member with the tray frame uppermost and the resilient top portions of the covering walls extending inwardly and downwardly about the upper edges of the tray member.
